ASSIGNORS, BY MESNE ASSIGNMENTS, TO SIMPLEX EQUIPMENT COMPANY, INC.,
OF NEW YORK, N. Y., A CORPORATION OF DELAWARE

BELT-TENSIONING DEVICE

Application filed September 14, 1926. Serial No. 135,357.

Our invention relates to generator mountings and drive mechanism in car lighting equipment and, more especially, to belt tightening devices for such generators.

5 An object of our invention is to provide a simple and effective device for insuring the desired tension of the belt for axle driven generators.

Another object of our invention is to provide 10 a simple and rugged belt tightening device that will be effective under all conditions of weather.

A further object of our invention is to provide 15 a belt tightening device that may be readily assembled to the generator mounting and replaced without adjusting the spring tension.

A still further object of our invention is to provide 20 a belt tension device which, in case of accident such as the breaking of the belt, will act as a buffer against the free swing of a generator and tend to bring said generator to rest without harm.

Another object is to provide a device of 25 the above-mentioned character that is well adapted to meet the varying conditions of hard practical use. Other objects will be in part obvious or in part pointed out hereinafter.

30 The invention accordingly consists in the features of construction, combinations of elements, and arrangements of parts as will be exemplified in the structure to be hereinafter described and the scope of the application 35 of which will be indicated in the following claims.

In the accompanying drawings in which is shown one of various possible embodiments of our invention,—

40 Figure 1 is a vertical longitudinal view showing the spring tension device in section.

Figure 2 is a horizontal plan view showing the spring housing and its connections.

45 Figure 3 is a vertical transverse view showing the open end of the spring housing and details of the generator suspension.

Figures 4 and 5 are enlarged views of the 50 closed end and open end, respectively, of the spring housing.

Figure 6 is a vertical transverse view show-

ing an alternative means for attaching the spring tension device.

Figure 7 is an enlarged view of the open end of the spring housing showing an alternative construction for retaining the spring 55 and followers.

Referring to the drawings in detail, like parts being designated by like reference characters, and first considering the embodiment illustrated in Figures 1 to 5, inclusive, a generator 1 is shown pivotally suspended by the arms 2 from a hinge pin 3 supported by the brackets 4 suitably secured to the car framing 5. A belt tensioning device or unit 6 is provided which at one end may be pivotally 60 connected to the car framing 5 through the bracket 7 and the pin 8. This device may comprise a spring housing or barrel 9 provided at its closed end with lugs 10 to receive the pin 8. Within the housing there may be 65 assembled a compression spring 11 between two thrust collars 12 and 13 connected by the thrust bolt 14, which may be provided at one end with a suitable head 15 and at the other with a threaded portion 16 to engage a 70 correspondingly threaded portion 17 of a shackle 18. The open end of the housing 9 may be partially closed by the inward extensions from the annular cap 19, secured by the bolts 20. The shackle 18 may be provided 75 with lugs 21 to engage, through the pin 22, a bracket 23 secured to one of the suspension arms 2 of the generator by the bolts and nuts 24 or other suitable means.

In operating position, the generator is 80 usually to the left of that shown in Figure 1 so that the tension of the belt 25, extending around the generator pulley 26 to operatively connect the generator with a cooperating pulley on the car axle (not shown), is normally determined by two factors, namely, the weight of the generator 1 and the thrust of the spring tension device 6 acting through its lever arm with respect to the hinge pin 3. It will be noted that as the belt is shortened and 85 the generator swings further to the left, from the position as shown in the drawings, the spring 11 would be further compressed under the action of the bracket 23 acting through the pin 22, the shackle 18 and the thrust col- 90

lar 13. However, it will also be noted that, as the generator swings further to the left and further compresses the spring, the effective lever arm of the spring is reduced while the effective lever arm of the weight of the generator is increased. Likewise should the generator swing to the right from the normal operating position, the compression of the spring would be reduced, its effective lever arm increased and the effective lever arm of the weight of the generator decreased so that by a proper proportioning of the related parts an approximately uniform tension or a desired variation of the tension of the belt may be obtained for any corresponding position of the generator throughout the operating range of the spring tension device.

Should, for some cause, the belt break as frequently occurs when the belt runs up on the flange of one of the pulleys, the generator would tend immediately to swing violently to the right under the combined action of gravity and the thrust of the spring. However, as soon as the compression spring 11 of the spring tension device has expanded to the limit permitted by the thrust bolt 15, any further movement of the generator to the right would tend to compress the spring and the action of the thrust bolt operating through the collar 12 would act immediately to restrain the generator from further swinging to the right and quickly bring the generator to a neutral position corresponding to the maximum expansion of the spring permitted by the thrust bolt and related parts. This feature of opposing motion in either direction from the neutral position, as indicated above, is of great practical advantage in the art of car lighting. Railway cars are frequently subjected to frequent violent jars and bumps, such as in coupling the cars together or in starting a train, and certain features of our invention make it possible to prevent violent swinging or oscillation of the generator, during such jarring and bumping of the cars, and particularly when the latter takes place while a belt is broken. It permits the construction of a spring tension device or unit which may be equally well applied to either side of the generator. In the preferred embodiment shown in the drawings, it is used as a compression member tending to thrust the generator away from the car axle but it may be equally well used on the side away from the axle as a tension member exerting a pull on the generator throughout its usual operating range, providing also the shock absorbing action as described above of opposing the violent swinging of the generator beyond the neutral position such as would be caused by breaking of the belt. Hitherto in car generator mountings the action of the spring device has been in one direction only and no buffer has been provided to absorb this violent swinging of the gen-

erator which occurs when the belt breaks or runs off a pulley with the result that the generator or mounting is frequently injured.

One of the difficulties hitherto encountered in devices of this character has been that the spring device is not protected from the elements so that in winter ice and snow have become frozen to the parts, thereby preventing effective operation. By housing the spring mechanism in the barrel 9 with the open end practically closed by the collar 13, protection from the weather is secured. By inclining the housing, as indicated in the drawings, any moisture which may collect therein from condensation or other causes will drain out of the open end through the opening in the cap 19. This cap is so designed that cinders, ice or other obstructions will find no lodgment within the barrel.

In the preferred form of our invention a long stroke compression spring is used, preferably set up to approximately three-fourths of its maximum compression so that there is little variation in the spring thrust throughout its working stroke. It will be noted that the spring tension device constitutes a unit which, after it is assembled in the factory, requires no further adjustment and may be readily applied to the generator mounting by swinging the generator to the right from the position as shown in the drawing until the distance between the pin 8 and the pin 22 corresponds to the distance between the holes in the lugs 10 and the holes in the lugs 21, thereby obviating the labor of tightening the spring to its working distortion which is a necessary feature of the devices in general use, where the spring is assembled to the generator mounting in an unrestrained condition or at free length. By utilizing a unit construction in which the spring is assembled in the factory under great initial compression, this invention provides a highly efficient device using a minimum amount of material which requires a minimum amount of space for its assembly and operation. It is also to be noted that the fact that no adjustment is required permits replacements to be made on the road without the necessity of highly skilled supervision.

Referring now to the embodiment of our invention illustrated in Figures 6 and 7, a modified form of connection between the belt tensioning device 6^a and the generator 1^a is there illustrated as well as a modified means for retaining the spring and follower assembly in the housing. In this embodiment, the shackle 18^a, instead of being connected to the pivoting arm 2^a of the generator, is connected to a supplemental arm or bracket 23^a which extends substantially radially from the generator and is preferably integral therewith. In other respects, this construction may be identical with that disclosed in connection with the first embodiment. The retaining

means shown in connection with this embodiment may be an annular plate 19 with inward projections or lips for preventing complete withdrawal of the assembled spring mechanism although, if desired, said plate may be replaced by pins 20^a extending transversely through apertures 19^a in the end of the barrel or housing 9^a. Said pins 20^a are preferably headed at one end and retained in assembled relation by means of cotters or the like. 27. These pins 20^a perform the same function as the tabs or inward projections on the annular cap 19 of the first embodiment by extending as chords across the open end of the housing 9^a for limiting outward movement of the spring and follower assembly. It is obvious that, if desired, these pins 20^a may be used in connection with the first embodiment instead of the annular cap 19. 20 It will thus be seen that there has been provided in this invention an apparatus in which the several objects hereinabove pointed out, together with many thoroughly practical advantages are successfully achieved and 25 that the apparatus is well adapted to meet the varying conditions of hard practical use.

As many possible embodiments may be made of the above invention and as many changes might be made in the embodiment 30 above set forth, it is to be understood that all matter hereinbefore set forth or shown in the accompanying drawings, is to be interpreted as illustrative and not in a limiting sense.

35 Having now described our invention, we claim:

1. In combination with a railway car, a generator, a belt adapted for driving the generator, means for pivotally suspending said generator and a spring for tensioning said belt, said spring being adapted during a portion of its operating range to add tension to said belt and during another portion of its operating range to restrict undue motion of said generator.

2. In combination with a railway car, a generator, a belt adapted for driving the generator, means for pivotally suspending said generator and a spring for tensioning said belt, said spring being also adapted to prevent harmful swinging of the generator in either direction.

3. In combination with a railway car, a generator, a belt adapted for driving the generator, means for pivotally suspending said generator and spring means for tensioning said belt, said spring means being adapted to be applied either to one side or to the opposite side of said generator.

4. In combination with a railway car, a generator, a belt adapted for driving the generator, means for pivotally suspending said generator and spring means for tensioning said belt, said spring means being double act-

ing and capable of application to one side or the other of said generator.

5. In combination with a railway car, a generator, a belt adapted for driving the generator, means for pivotally suspending said generator and a spring device for tensioning said belt and preventing harmful swinging of said generator, said device being capable of application to either side of said generator.

6. In combination with a railway car, a generator, a belt adapted for driving the generator, means for pivotally suspending said generator and a spring tension unit for tensioning said belt, said unit being under initial distortion and adapted to be applied to said device, without further adjustment, on either side of said generator.

7. In combination with a railway car, a generator with an arm extending therefrom, a belt adapted for driving the generator, means for pivotally suspending said generator, and spring means connected to said arm for tensioning said belt, said spring means being capable of application to either side of said generator.

8. In combination with a railway car, a generator with an arm extending therefrom, a belt adapted for driving the generator, means for pivotally suspending said generator and a spring unit connected to said arm for tensioning said belt and preventing harmful swinging of the generator in either direction, said spring unit being adapted for application to either side of said generator.

9. In car lighting equipment, in combination with a generator pivotally mounted beneath the car and adapted to be driven by a belt from the car axle, a belt tensioning device comprising a housing, a spring enclosed in said housing, and means connecting said spring with said generator whereby swinging movement of said generator in either direction with respect to said housing will cause further compression of said spring.

10. In car lighting equipment, in combination with a generator pivotally mounted beneath the car and adapted to be driven by a belt from the car axle, a belt tensioning device comprising a housing, a spring mounted therein, thrust collars one at each end of said spring, and a thrust bolt for connecting said two collars, and means connecting said bolt with said generator so that movement of said generator in either direction will cause further compression of said spring.

11. In car lighting equipment, in combination with a generator pivotally mounted beneath the car and adapted to be driven by a belt from the car axle, a belt tensioning device comprising a housing, a compressed spring contained in said housing, a pair of movable thrust collars in said housing one at either end of said spring, a bolt passing through one of said thrust collars and rigidly connected to the other of said thrust collars,

and means connecting said last thrust collar to said generator, said bolt having an enlargement at the end thereof exterior of said first thrust collar.

5 12. In car lighting equipment, in combination with a generator pivotally mounted beneath the car and adapted to be driven by a belt from the car axle, a belt tensioning device comprising a spring, means connecting said spring with said generator so that movement of said generator in either direction will be opposed by said spring, and a housing for enclosing said spring.

15 13. In car lighting equipment, in combination with a generator pivotally mounted beneath the car and adapted to be driven by a belt from the car axle, a spring tending to swing said generator away from said axle when said generator is in normal operating 20 position and adapted when said generator swings out of normal operating position in a direction away from said car axle to tend to urge said generator toward said car axle.

25 14. In car lighting equipment, in combination with a generator pivotally mounted beneath the car and adapted to be driven by a belt from the car axle, a spring acting upon said generator adapted to yieldingly resist swinging movement of said generator in 30 either direction out of its normal operating range.

35 15. In car lighting equipment, in combination, a generator mounted beneath the car to swing toward and away from an axle of the car, a belt for driving said generator from said car axle, a compression spring, means connecting said spring to tend to swing the generator in a direction away from the car axle so as to normally tension said belt, said 40 connecting means being adapted to cause said spring to oppose swinging movement of said generator in the opposite direction out of normal operating position when the belt breaks.

45 In testimony whereof we affix our signatures.
